UNITED STATES PATENT OFFICE

118,151

DESIGN FOR AN AUTOMOTIVE RADIO SET

George W. Bill, Cincinnati, Ohio, assignor to The Crosley Corporation, Cincinnati, Ohio, a corporation of Ohio

Application January 26, 1939, Serial No. 82,621

Term of patent 7 years

To all whom it may concern:

Be it known that I, George W. Bill, a citizen of the United States and a resident of Cincinnati, in the county of Hamilton and State of Ohio, have invented a new, original, and ornamental Design for an Automotive Radio Set, of which the following is a specification, reference being had to the accompanying drawing, forming a part thereof.

In the drawing:

cluding the control means of the radio set on the same scale as the view of Figure 1.

The side of the radio set not illustrated is the same as the side shown.

I claim:

The ornamental design for an automotive radio set, substantially as shown and described.

GEORGE W. BILL.
